[57] ABSTRACT

A pre-fabricated fireplace adaptable for assembly about an existing vertical column, the device consisting of an inverted conical base, and a conical hood, both of which clamp about a vertical column, together with grate supporting structure and an internal shield for the hood. A circular curtain screen is hung from the hood over the base and the exhaust pipe may be mounted concentrically about the support post.

PATENTED DEC 11 1973

3,777,735

FIG. 3

FIG. 1

FIG. 2

DECORATIVE FIREPLACE

SUMMARY OF THE INVENTION

This invention relates to a circular fireplace mounted about a central vertical support column, and particularly to a fireplace which may be mounted on an existing vertical column.

The fireplace may be pre-fabricated so as to be readily assembled by the user.

The fireplace consists of an inverted truncated cone for the base member and a second truncated cone for the hood. Each cone is fabricated with an open radial seam to enable the cones to be mounted on existing vertical columns, with the seam being joined by a locked member when installed.

A circular curtain screen may be hung from the hood over grate area of the base. The grate area is supported by circular pan mounted to the base cone. The exhaust pipe for the fireplace consists of a concentric tube mounted about the vertical support member.

DESCRIPTION OF THE DRAWING

The objects and features of the invention may be understood with reference to the following detailed description of an illustrative embodiment of the invention taken together with the accompanying drawing in which:

FIG. 1 is a perspective view of the assembled fireplace;

FIG. 2 is a cross-section in elevation of the assembled fireplace; and

FIG. 3 is a cross-section of the lock seam used to form the joints of the unit.

DESCRIPTION OF THE PREFERRED EMBODIMENT

Turning now descriptively to the drawing, in which similar reference characters denote similar elements throughout the several views, FIG. 1 and FIG. 2 illustrate the fireplace 10 assembled about vertical column 11 with hood 12 and base 13 each clamped to vertical column 11.

Both hood 12 and base member 13 are in the form of truncated cones of sheet metal, and are fastened to the vertical column 11 by means of clamps 19.

A plate 18 is fastened in base member 13 to provide support for the grates and logs 15, and affix the top of base member 13, and a similar plate 17 may be used to close and affix the upper interior section of the hood 12. Both plates 17 and 18 may be formed with curled lips 31 to cover the exposed sheet metal edges of cones

12 and 13.

A circular screen curtain 14 may be hung from rails 16 fastened to the interior of hood 12 so as to enclose the grate area and the logs 15.

Exhaust pipe 26 is fastened concentrically about the exterior of the vertical column 11, joining the hood 12. The exhaust pipe 26 may be joined to the hood 12, or fastened independently to the column 11.

Plate 17 encloses the interior of the hood 12. In an alternate embodiment, a fan 28 equipped with a heater element may be mounted in plate 17 so as to blow warm air into the area. In order to install the device 10 about an existing vertical column 11, the various components may be formed with open seams which are locked to become closed joints 22 after installation as shown in FIG. 3.

The edges of each metal sheet 34 is formed with an open lip 35 at the seam and two such lips 35 are bound together by key member 36 which is formed with mating lips 37. Preferably the lips 35 are bent to the interior of each section so that the finished joint line 22 will not interfere with the exterior appearance of the unit.

The base of the unit may be protected by a base pan 20 fastened with nails 29 to the floor 30. This pan may be filled with gravel 21 or other such material with decorative properties.

Since obvious changes may be made in the specific embodiment of the invention described herein without departing from the scope thereof, it is indicated that all matter contained herein is intended to be interpreted in an illustrative and not a limiting sense.

I claim:

1. A circular fireplace unit adaptable for mounting about an existing vertical column closed at its upper and lower ends, as a means of decorating and concealing the column, comprising a hood of sheet metal formed in the shape of a truncated cone, and a base section formed of sheet metal in the form of an inverted truncated cone, with means to clamp both hood and base member to a vertical column, said hood and base members each initially formed with an open radial seam, together with locking means to close said open seam of each member after mounting about a vertical column.

2. The combination as recited in claim 1 together with an exhaust pipe leading from the hood section, said exhaust pipe being adaptable to being mounted in a concentric manner about the vertical column to which the hood is mounted, said exhaust pipe initially formed with an open seam along its length.
